Primary Examiner — Phillip S Hyder*Assistant Examiner* — Sydney Buffalow(74) *Attorney, Agent, or Firm* — Greenberg Traurig LLP;
Franklin D. Ubell(57) **CLAIM**

The ornamental design for a single wall display, as shown and described.

DESCRIPTION

FIG. 1 is a front perspective of the single wall display;
 FIG. 2 is a second front perspective view of the display;
 FIG. 3 is a front plan view of the display;
 FIG. 4 is a top view of the display;
 FIG. 5 is an end view of one end of the display; and
 FIG. 6 is an end view of the opposite end of the display.
 The broken lines shown in the drawings are for illustrative purposes only and form no part of the claimed design.
